(No Model.)

E. WRIGHT.

CONDENSER FOR FINISHER CARDS.

No. 340,929.

Patented Apr. 27, 1886.

Fig:1.

UNITED STATES PATENT OFFICE.

ELIJAH WRIGHT, OF NORTH ANDOVER, MASSACHUSETTS, ASSIGNOR TO THE
DAVIS & FURBER MACHINE COMPANY, OF SAME PLACE.

CONDENSER FOR FINISHER-CARDS.

SPECIFICATION forming part of Letters Patent No. 340,929, dated April 27, 1886.

Application filed February 8, 1886. Serial No. 191,170. (No model.)

To all whom it may concern:

Be it known that I, ELIJAH WRIGHT, of North Andover, county of Essex, and State of Massachusetts, have invented an Improvement 5 in Condensers for Finisher-Cards, of which the following description, in connection with the accompanying drawings, is a specification, like letters on the drawings representing like parts.

The rub-rolls for both doffers as now commonly used in connection with finisher-cards are mounted in bearings erected in carriages adapted to be reciprocated in guides of a frame attached to the frame-work of the machine, and both sets of rub-rolls are held in the 15 same frame, and the stripper-rolls next to the doffers, and between them and the first top rub-roll of each set of rub-rolls, are one above the other in the same vertical plane.

To enable each set of rub-rolls, with its co-operating stripper-roll, to be adjusted independently of each other with relation to each doffer, to compensate for unequal wear of the doffer, and also to adapt the position of the rub-rolls horizontally to any variation in the 25 position of the doffers or to doffers differing in diameter, I have divided horizontally the frame carrying the rub-rolls into, as herein shown, two parts, and have arranged one upon the other, and connected the two parts adjustably together.

My invention consists, essentially, in a frame containing a set of rub-rolls, combined with a second superimposed independent frame containing a set of rub-rolls, one frame being 35 made adjustable horizontally upon the other at right angles to the length of the rub-rolls, to enable each set of rub-rolls to be placed at the proper distance from the doffer with which it is to co-operate, substantially as will be described.

Figure 1 in side elevation shows portions of a finisher-card with my improved condenser attached thereto, the card-clothing being, however, omitted; Fig. 2, a section thereof in the 45 line xx of Fig. 1, looking toward the left, one of the eccentric-straps, and one of the rods being partially broken out, the said figure showing only that end of the two frames at which the rub-rolls derive their reciprocating movement, the opposite ends of the said frames be-

ing the same in construction as the end frames shown, the opposite ends of the said rolls, and the usual mechanism for rotating them, and also the guides cut by the said dotted lines, are omitted to avoid confusion in the drawings; 55 and Fig. 3, a separate detail chiefly to show one of the spherical boxes.

A is the frame-work, and B the main cylinder, both of usual construction.

Prior to my invention the rubbing rolls of 60 the condensing mechanism have both been placed in one frame with their axes of rotation in the same vertical line.

In accordance with my invention I divide 65 the condenser into two or more parts or frames, as at E E', and connect the same adjustably.

As herein shown, the connection between the separate parts or frames E E' is made by bolts a , extended through slots in the top and bottom plates of the said frames, and to provide for their adjustment when the said bolts are loosened I have herein shown screws e extended through one frame, they striking lugs or projections e^2 of the other frame, the said lugs (herein shown as attached to the upper frame, E) being extended through slots in the lower frame.

By the term "frame" I mean to include uprights of like general shape at opposite sides of the carding-machine, the said uprights at 80 opposite sides of the carding-machine being connected, as, for instance, by a rod a^2 , or any suitable bar extended from one to the other, the said rod being passed through part of the upper frame, E', the lower part of the frame 85 E being connected, as usual, by bolts 62 to the frame of the carding-machine.

The frame E has two reciprocating carriages, d^3 d^4 , which slide on guides 33 and have usual bearings for the upper and lower rub-rolls, d^2 90 and d' , and next to one of the upper rolls, and between it and the doffer D, is located the stripper-roll d .

The frame E', mounted adjustably upon the frame E, has usual guides, 22, for the reciprocating carriages c^1 c^2 , which have bearings for the lower and upper rub-rolls, c' and c^2 , and between one of the upper rub-rolls and the doffer C is located the stripper-roll c .

The rub-rolls are reciprocated, in usual man-

ner, by eccentrics on an upright shaft, G, having at its lower end a bevel-gear, 10, driven from a bevel-gear, 12, on a shaft, 13, common in finishing-cards. The eccentrics 65 on the 5 shaft G are embraced by eccentric-straps 14, the rods of which embrace studs 15 of the said carriages, and to permit adjustment of the frames the said rods are provided with holes made to resemble two cones with their apices 10 together, as shown in section, Fig. 2.

The upper and lower journals of the shaft G are made to enter holes in pipe-boxes f', which externally are made spherical, as best shown in Fig. 3, to fit concaved bearings 66, having concaved caps f'', the spherical shape given to the pipe-boxes enabling the shaft to be tipped out of vertical position when the frames are adjusted one on the other to place the rub-rolls and the stripper-rolls in correct working position with relation to the doffers C and D.

I have herein shown two separate frames, E E', with their series of rub-rolls to co-operate with two doffers; but I desire it to be understood that I may use more than two frames, 25 one mounted above and made adjustable on the other, each frame having its proper set of rub-rolls, there being a doffer for each set of rub-rolls.

I do not desire to limit my invention to the 30 employment of the particular mechanism shown for actuating the rub-rolls.

Instead of the particular devices shown to connect the frames E E' together, and to adjust the same one on the other in a direction at 35 right angles to the length of the rub-rolls, I may employ any other well-known equivalent devices.

The rub-rolls may be rotated by means of gearing substantially such as shown in United

States Patent No. 238,329, or in other usual 40 manner.

I claim—

1. A frame containing a set of rub-rolls, combined with a second superimposed independent frame containing a set of rub-rolls, one 45 frame being adjustable horizontally upon the other at right angles to the length of the rub-rolls to enable each set of rub-rolls to be placed at the proper distance from the doffer with which it co-operates, substantially as described.

2. Two or more doffers, two or more sets of rub-rolls, and their co-operating stripper-rolls, combined with two or more separate frames, and carriages therein to support the journals 55 of the said rolls, one frame, with its set of rub-rolls and stripper-rolls, being made adjustable on or with relation to the other frame and its set of rub-rolls and stripper-rolls to insure the placing of the said rub or stripper rolls at 60 the proper distance from the said doffers, substantially as and for the purpose described.

3. The two independent frames E E', made adjustable one on or with relation to the other, 65 their carriages, rub-rolls supported thereon, and the upright shaft provided with eccentrics, and the connecting-rods, combined with the spherical pipe-boxes, and in which the said shaft has its journals and bearings therefor, substantially as described.

In testimony whereof I have signed my name to this specification in the presence of two subscribing witnesses.

ELIJAH WRIGHT.
